UNITED STATES PATENT OFFICE

STANLEY J. KUZIEL, OF HOLYOKE, MASSACHUSETTS.

COUNTER FOR STAMP-AFFIXING MACHINES.

Original application filed June 28, 1924, Serial No. 723,054. Divided and this application filed November 28, 1924. Serial No. 752,647.

To all whom it may concern:

Be it known that I, STANLEY J. KUZIEL, a citizen of the United States, and resident of Holyoke, in the county of Hampden and 5 State of Massachusetts, have invented certain new and useful Counters for Stamp-Affixing Machines, of which the following is a specification.

This invention relates to improvements in 10 counters, particularly counters to be used with envelope stamping machines as described in my co-pending application Serial No. 723,054, filed June 28, 1924, of which this application is a division.

15 It is the principal object of my invention to provide a counter adapted to be operated by the rod of the stamping machine acting as a plunger for affixing the stamp to an envelope and counting the number of stamps so used, and a counter which permits either 20 the counting of a limited number of stamps or the counting of considerable quantities, if a great number of stamps is used.

Another object of the invention is the 25 provision of a counter which can readily be operated even by unskilled operators and which will perform its work positively and accurately.

A further object of the invention is the 30 provision of a counter which automatically and visibly displays the number of stamps used behind a window, or windows.

A still further object of the invention is the provision of a counter of this type which 35 counts a predetermined number of stamps automatically and a multifold of this number by automatically coupling the band displaying the predetermined number with another band displaying multifolds of this 40 number each time the predetermined number has been reached and uncoupling both bands after the display of each multifold number.

These and other objects and advantages 45 of my novel and improved counter will become more fully apparent as the description thereof proceeds, and will then be specifically pointed out in the accompanying claims appended hereto.

In the accompanying drawings, forming a 50 material part of this disclosure:

Figure 1 is a top plan view of a machine equipped with a counter constructed according to the present invention.

Figure 2 is an end view of the machine

and counter seen in the direction of the 55 arrows 2-2 of Figure 3.

Figure 3 is a fragmentary rear view of the counter.

Figure 4 is an end view of the machine and counter looking in the direction of the 60 arrows 2-2 of Figure 3, with the casing broken away.

To the rear wall of a stamping machine for envelopes of any desired type as for instance described in my above mentioned 65 co-pending application, a casing 10 for a counter is affixed in the manner clearly shown in Figure 1.

The counter comprises a pair of comparatively large rollers 11 and 12 on a shaft 13 70 over which are guided the endless bands or tapes 14 and 15, the inner one, 14, bearing the numerals 1 to 50 inclusive, while the outer tape, 15, bears the numbers 50, 100, 150 and so on, always displaying the main- 75 fold of 50.

The bands or tapes 14 and 15 are also guided at the opposite end of the machine over suitable, smaller guide rollers 16, 17 80 on a divided shaft 18. This shaft carries between the rear wall 19 of the machine and the inner roller 16, a sprocket wheel 20 between the teeth of which the lower downwardly directed end of an arm 21 extends 85 on which a collar 22 keyed to a rod 23 rests having an operating knob 24 at its upper end and carrying at its lower end the stamp affixing plate 25 so that upon the operation of the rod 23 or plunger to affix one stamp to an envelope resting on table 26, the 90 sprocket wheel 20 will be turned or advanced one step, and the tape guided over wheel 16 on shaft 18 is also advanced one step represented by the numerals carried thereby, so that the number of stamps used 95 will appear before a window 27 in the casing 28 enclosing the rollers and the tapes, so for instance as shown as an example in Figure 2, the numeral "38" will appear in the window if 38 stamps have been used. 100

On a lower shaft 29 within casing 10 are secured two independently moving feed rollers 30 and 31 respectively for the tapes 14 and 15, and between said rollers, the shaft carries a small gear 32 in mesh with a large 105 gear 33 on the part of the shaft 18 carrying the roller 17 for the outer tape 15.

A stop or shifter 34 provided with teeth

and having the form of an arc is secured to the band 14 opposite the numeral 50 thereon so that after affixing 50 stamps to an envelope held in the machine, it will engage 5 the gear 32 and turn the large gear 33 to move the roller 17 and band 15 thereon forward for one step to indicate behind a window 35 in casing 28 (Figure 2), the 10 total number of stamps or the manifold 10 of 50.

The counter operates as follows:—

Upon the operation of the plunger rod 23 to affix a stamp to an envelope in the machine, the counter operating arm 21 is also 15 depressed and will advance sprocket wheel 20 one step and this motion will be communicated to the band 14 guided over roller 16, so that the numeral 1 will appear behind the window 27 and so forth until 50 stamps 20 have been used or affixed, when the shifter 34 will come into engagement with the gear 32 in mesh with gear 33 and feed the same one step so that the numeral "50" on strip or 25 tape 15 appears behind window 35. Upon further operation of plunger 23 and finger 21 the engagement between finger or shifter 34 and gear 32 will be interrupted and the band 15 will remain at rest as the shaft 18 is divided until 100 stamps have been used, 30 whereupon the numeral "100" will appear behind window 35 in the manner as de-

scribed above with respect to number "50" and so on.

It will be clear that such changes may be made in the general arrangement and in the 35 construction of the minor details of my counter as fall within the scope of the appended claims without departure from the spirit of the invention.

Having thus described my invention, what 40 I claim as new and desire to secure by Letters Patent is:

1. In a counter having parallel, independently movable bands, one bearing a suitable range of numerals, the others bearing 45 multiples of the range of the first band, and means to impart a step-by-step motion to the first band, an arc shaped coupler provided with teeth and carried upon the lower order bands. 50

2. In a device according to claim 1, gearing associated with the higher order bands adapted to be engaged by the teeth of said coupler to advance the said bands for one step upon the completion of a count corresponding to the range of the lower order bands. 55

Signed at Holyoke, in the county of Hampden and State of Massachusetts, this 17th day of November A. D. 1924.

STANLEY J. KUZIEL.
